UNITED STATES PATENT OFFICE.

JERALD G. DOTY, OF ST. LOUIS, MISSOURI; LELA M. DOTY, ADMINISTRATRIX OF SAID JERALD G. DOTY, DECEASED, ASSIGNOR TO J. G. DOTY PUMP COMPANY, OF ST. LOUIS, MISSOURI, A CORPORATION OF MISSOURI.

LIQUID-DISPENSING APPARATUS.

Application filed January 8, 1926. Serial No. 79,926.

This invention relates to liquid dispensing apparatus.

An object of the invention is to provide a liquid dispensing apparatus with equipment for automatically controlling the amount of liquid passing to the apparatus for delivery therefrom.

The invention shown is embodied in a liquid dispensing apparatus having a supply pipe 10 for conducting liquid thereto and an overflow pipe for conducting liquid from the apparatus in excess of the measured amount desired. The invention is arranged so that liquid passing through the overflow pipe 15 will operate mechanism to stop flow of liquid to the apparatus through the supply pipe.

Fig. 1 is a view showing the invention embodied in a form to control the motor of a pump whereby delivery of liquid to a dispensing apparatus is controlled.

Fig. 2 is an enlarged plan view of the mechanism for controlling the motor.

Fig. 3 is a side elevation of the motor controlling mechanism, the housing therefor being shown in section.

The drawings exhibit so much of a liquid dispensing apparatus as will suffice to show the connection of the invention therewith.

A supply pipe 1 is equipped with a pump 2 of any known construction by operation of which liquid will be forced upwardly through the pipe 1 to a receptacle (not shown) from which the liquid is distributed. A sprocket wheel 3 is rigid on the shaft 4 of the pump and is driven by a connection 5 operated by an electric motor 6.

Electric wires 7 from the motor are connected to the respective binding posts 8 (Fig. 2), each of which is in connection with a contact member 9 on a block 10 of insulating material and spaced from the contact members 11 with which the respective wires 12 are connected. A lever 13 has a pair of lateral projections 14 pivotally seating in notches 15 in arms 16 and retained in such connection by a spring 17 connecting the lever 13 with a lever 18 having similar pivotal connection 19 with the arms 16. By oscillating the lever 18 to move the outer end thereof above or below the plane of the pivots 14 of the lever 13, said lever 13 will be raised or lowered by the power of the spring 17. An insulating arm 20 in connection with the free end of the lever 13 sup-

ports a pair of switch elements 21 for opening and closing the circuits from the respective contact members 11 of the corresponding contact members 9 whereby the operation of the motor is controlled.

A rod 22 has its outer end equipped with a handle 23 and its inner end pivoted to an upwardly extending arm of a bell crank lever 24 rigid with a rocking pivot 25 extending through the wall of the housing 26 enclosing the switch mechanism above described and attached to the lever 18. The horizontal arm of the lever 24 carries a weight 27 tending to operate said lever in a direction to raise the switch members 21 out of contact with the switch members 9 and 11 to open the switches. By pushing the lever 22 inwardly the lever 18 will be lowered to the position shown in Fig. 3, with the result that the switches are closed and the motor is caused to operate the pump to deliver liquid to the dispensing device.

A lever 28 pivotally supported at 29 has its opposite end connected to the lower end of a link device 30, the upper end of which is pivoted to an arm 31 attached to the outer end of a hinge pin 32 mounted for rocking movements in a valve chamber 33. A gate valve 34 is supported by the hinge pin 32 in the valve chamber 33. The valve chamber 33 is in connection with the overflow pipe 35 so that when the liquid overflows from the dispensing receptacle (not shown) the weight of the liquid in the overflow pipe will depress and open the gate valve 34. This raises the arm 31, the link 30 and the end of the lever 28.

The vertical arm of the lever 24 has a projection 36 extending under the lever 28 and provided with a notch 37 adapted to be engaged by a shoulder 38. So, when the rod 22 is pushed inwardly the projection 36 becomes engaged with the shoulder 38 thus holding the electric switches closed. The gate valve 34 is held closed by the weight of the connections therefrom to the lever 28. When the gate valve 34 is weighted by the overflow liquid it is thereby opened, with the result that the lever 28 is raised to disengage the shoulder 38 from the notch 37 whereupon the weight 27 operates the lever 24 to open the electric circuit switches as previously described. This causes the motor and the pump to stop with the result that

the flow of liquid to the dispensing device ends.

The electric circuit wiring is confined in tubes 39 and the other electrical connections are enclosed so that it is impossible for any liquid or other foreign substances to come into contact with the wiring or connections thereof. Thus all danger of short circuiting and conflagration is eliminated.

10 In the practical form shown and described my invention has met an existing need for automatic control of the flow of liquid to the dispensing device, so that the entire attention of the operator may be devoted to other duties. This prevents loss of time and permits service to be rendered to more patrons than is possible by use of dispensing devices requiring the attention of the operator to the supply controlling 20 mechanism.

I am aware that the construction and relationship of the parts may be varied considerably without departure from the nature and principle of the invention.

25 What I claim and desire to secure by Letters Patent is:—

1. In a liquid dispensing apparatus, the combination with mechanism controlling flow of liquid, and a pipe for conducting 30 the controlled liquid, of a pivoted element in said pipe movable by the liquid passing through said pipe, a device settable in one position to cause said mechanism to operate and in another position to cause said mechanism to stop, engaging elements holding said device in position to cause said mechanism to operate, a spring for moving said device to said two positions, and means operated by said pivoted element for disengaging said 35 elements and causing said spring to move said device to position to cause said mechanism to stop when said element is moved by liquid passing through said pipe.

2. In a liquid dispensing apparatus, the combination with mechanism controlling flow of liquid, and a pipe for conducting the controlled liquid, of a pivoted element in said pipe movable by the liquid passing through said pipe, a device settable in one 45 position to cause said mechanism to operate and in another position to cause said mechanism to stop, engaging elements holding said device in position to cause said mechanism to operate, a spring for moving said device to said two positions, means operated by said pivoted element for disengaging said 50 elements and causing said spring to move said device to position to cause said mechanism to stop when said element is moved by liquid passing through said pipe, and manual means for causing said spring to move said device to position to cause said mechanism to operate.

3. In a liquid dispensing apparatus, the combination with mechanism controlling

flow of liquid, and a pipe for conducting the controlled liquid, of a pivoted element in said pipe movable by the liquid passing through said pipe, a device settable in one position to cause said mechanism to operate and in another position to cause said mechanism to stop, engaging elements holding said device in position to cause said mechanism to operate, a spring for moving said device to said two positions, means operated by said pivoted element for disengaging said elements and causing said spring to move said device to position to cause said mechanism to stop when said element is moved by liquid passing through said pipe, and manual means for causing said spring to move said device to position to cause said mechanism to operate, said manual means also moving said element to position in which it will be operated by liquid passing through said pipe.

4. In a liquid dispensing apparatus, the combination with mechanism controlling flow of liquid, and a pipe for conducting the controlled liquid, of an element in said pipe movable to and from position to be operated by the liquid passing through said pipe, a device settable in one position to cause said mechanism to operate and in another position to cause said mechanism to stop, engaging elements holding said device in position to cause said mechanism to operate, an actuator for moving said device to said two positions, manual means for causing said actuator to move said device to position to cause said mechanism to operate, and connections from said element for disengaging said engaging elements and permitting said actuator to move said device to position to cause said mechanism to stop when said first named element is moved by liquid flowing through said pipe.

5. In a liquid dispensing apparatus, the combination with mechanism controlling flow of liquid, and a pipe for conducting the controlled liquid, of an element in said pipe movable by the liquid flowing through said pipe, a machine for operating said mechanism, a device settable in one position to cause said machine to operate and in another position to cause said machine to stop, engaging elements holding said device in position to cause said mechanism to operate, an actuator for moving said device to each of said two positions, connections operated by the liquid flowing through said pipe for disengaging said engaging elements and causing said actuator to move said device to position to cause said machine to stop, and a manipulative part causing said actuator to move said device to position to cause said machine to operate.

6. In a liquid dispensing apparatus, the combination with mechanism controlling flow of liquid, and a pipe for conducting the

controlled liquid, of an element in said pipe movable by the liquid flowing through said pipe, a machine for operating said mechanism, a device settable in one position to cause said machine to operate and in another position to cause said machine to stop, engaging elements holding said device in position to cause said mechanism to operate, an actuator for moving said device to each of said two positions, connections operated by the liquid flowing through said pipe for disengaging said engaging elements and causing said actuator to move said device to position to cause said machine to stop, and a manipulative part causing said actuator to move said device to position to cause said machine to operate and for causing said connections to move said first named element to position for operation by liquid flowing through said pipe.

7. In a liquid dispensing apparatus, the combination with mechanism controlling flow of liquid, and a pipe for conducting the controlled liquid, of an element in said pipe movable to and from position to be operated by liquid flowing through said pipe, a device settable in one position to cause said mechanism to operate and in another position to cause said mechanism to stop, engaging element holding said device in position to cause said mechanism to operate, an actuator for moving said device to each of said two positions, connections operated by said element when said element is moved by liquid flowing through said pipe for disengaging said engaging elements and causing said actuator to move said device to position to cause said mechanism to stop, and a manipulative part for moving said device to position to cause said mechanism to start and for moving said first named element to position to be operated by liquid flowing through said pipe.

JERALD G. DOTY.
